UNITED STATES PATENT OFFICE.

JOHN EDMUND PERRY, OF SHARON, PENNSYLVANIA, ASSIGNOR TO VALLEY MOULD & IRON CORPORATION, OF SHARPSVILLE, PENNSYLVANIA, A CORPORATION OF NEW YORK.

CLOSED-BOTTOM INGOT MOLD.

Application filed May 27, 1925. Serial No. 33,126.

The present invention relates broadly to metallurgy and more especially to a closed bottom ingot mold provided with cast chilled supporting surfaces upon the bottom of the mold.

Heretofore in the art of casting closed bottom ingot molds it has been customary to cast these ingot molds in a flask with the closed end of the ingot mold cast at the top 10 of the flask. This left a very uneven surface on the part which subsequently became the bottom of the ingot mold and it was necessary to cast the ingot mold considerably longer than the length desired for the 15 finished ingot mold in order to allow for machining, to cut away the kish and spongy metal and provide a smooth surface for the bottom portion of the ingot mold when in use so that it could be properly seated on a 20 suitable stool.

The present invention overcomes the difficulties of the known art without adding any undesirable features and comprises a closed bottom ingot mold in which the 25 necessity for machining is entirely obviated and in which the extra metal heretofore used in casting has been eliminated.

One object of the present invention comprises a closed bottom ingot mold having a 30 portion of the bottom surface chilled to comprise a supporting surface.

Other objects and desiderata of the present invention will in part be obvious and will in part be pointed out hereinafter in the 35 specification following by reference to the accompanying drawings in which like characters are used to represent like parts throughout the several figures thereof.

The disclosure herewith is intended to be 40 illustrative of a preferred form of the invention but it is realized that the invention may be embodied in constructions other than those herein specifically disclosed and therefore the disclosure herewith is to be understood as illustrative and not in the limiting 45 sense.

Figure 1 is a sectional view of one form of flask, etc., for carrying out the present method.

50 Figure 2 is a plan view of the constructions disclosed in Figure 1.

Figure 3 is a plan view of one of the chill top plates.

Figure 4 is an elevation of one of said chill top plates.

Figure 5 is a sectional view of an ingot mold in accordance with the present invention set up ready to cast ingots.

The present invention comprises an ingot mold having a closed bottom and with 60 smooth supporting surfaces on a portion of the bottom. This mold is arranged with a body portion 22, a chilled mouth 24, and with smooth supporting surfaces 15 between which extends a roughening unchilled portion 20. The smooth supporting surfaces are adapted to set on a suitable casting stool 23 which is provided with edges 17 and 18 upon which the smooth surfaces 15 are adapted to rest when the mold is set up for 70 casting. The sides of the mold adjacent the lower portion thereof are provided with staples 12 adapted for use in handling a mold and the top of the mold carries a hot top 25 which may be utilized to preserve 75 the upper metal hot at the end of the casting operation. The bottom of the mold carries a sand or other frangible plug 24 which may be broken out after the ingot has frozen in order to provide an opening for stripping 80 the ingot from the mold.

In order to facilitate a complete understanding of the ingot mold comprising the present invention, it may be well to refer to one method by which the mold can be made. This method comprises setting up a sand flask 2 on a casting bottom 1 with the sand matrix 4 around a suitable core 5 of the shape to form the interior of the ingot mold to be cast. This core 5 preferably carries 85 an extension 6 which forms an opening in the bottom of the ingot mold 22 when the casting operation is finished. Chill plates 7 centered by dowels 8 are held in position on the flask by C-clamps 9. The chill plates 90 preferably terminate in bevelled edges 10. A suitable gate 11 is also provided in such manner that the flask may be bottom poured as is well known in the art. The staples 12 are set in the sand walls in such manner as 95 to be cast solidly into the ingot mold.

The bottom pouring of the set up described causes the metal to rise between the chill plates 7 so that the kish, impurities and spongy metal may be raked off the top when 105 the flask is filled.

The ingot mold resulting from this operation has chilled supporting surfaces cast on the bottom thereof and with the rough portion 20 on the bottom of the mold between the smooth surfaces adapted to extend into the trough 19 of the casting bottom 23 so that the rough portion does not in any way interfere with the efficient operation of the mold. The mold having chilled supporting surfaces is adapted to withstand hard usage and is less liable to crack during use because of the chilled metal which supports the adjoining metal in the side walls at the bottom of the mold in which the curved portion of the matrix is located.

The bevelled edges 10 on the chill plates 7 produce downwardly inclined finished bevelled edges on the bottom of the mold. These bevelled edges on the bottom of the mold cooperate with complementary bevelled edges on the supporting base 23 to automatically and accurately guide the mold into position on this base or stool, when the mold is lowered in place by a suitable crane 25 to permit the surfaces 15 on the bottom of the mold to cooperate with the rails or edges 17 and 18 on the base 23.

This mold base or stool 23 comprises flat topped rails 17 and 18 which are adapted 30 to form the supporting members for the mold. Bevelled faces extend downwardly and inwardly from the top of the rails 17 and 18 and lead to a valley or trough 19 of sufficient depth to accommodate the rough portion 20 on the bottom of the mold. Preferably, a clearance opening 21 is provided in this valley portion 19 to accommodate a mold plug 24 such as is commonly used with molds of this type. The construction 40 of the bevelled edges on the bottom of the mold and on the stool is of considerable importance. These molds are very heavy and are handled by cranes, and in lowering a mold in place on its stool, it is essential 45 that the mold shall be guided into position to stand firmly on the stool and therefore, the part 20 on the mold acts to insure this relation. Where extension 20 has substantially straight sides, or the stool is without 50 guiding means, there is danger of the mold being lowered with one of the corners of the rough extension resting on the straight side of the stool. This situation may not be observed until the supporting chains 55 from the crane have been substantially relieved from strain, at which time the mold is liable to drop suddenly into position with a very heavy impact, which may either crack off a portion of the mold or stool, or worse 60 still may seriously injure a workman. The inclined interlock in this present invention between the bottom of the mold and the mold supporting base avoids this difficulty, in that the small end of the mold is easily 65 guided between the trough rails and by

watching one side of the mold as the crane lowers the mold into position, the workman is assured that the other side is automatically being guided into place by the mold base.

Having thus described my invention, what I claim is:

1. The combination of a closed bottom ingot mold having cast finished supporting surfaces arranged on each side of the bottom thereof, a depending portion between the said surfaces, inclined surfaces on the sides of said depending portion, and supporting base comprising an open trough of a depth greater than the length of the depending portion of said ingot mold, the inner sides of said trough being inclined and the construction and arrangement being such when said mold is seated on said supporting base the said mold rests entirely upon said supporting cast finished surface with the central portion of said mold out of contact with said supporting base.

2. As an article of manufacture, a supporting base for closed bottom ingot molds, said supporting base comprising a pair of parallel supporting edges with a deep trough-like depression extending between said supporting edges and adapted to be out of contact with the bottom of an ingot mold to permit said supporting edges to support the mold.

3. As an article of manufacture, a supporting base for closed bottom ingot molds, said supporting base comprising a pair of parallel supporting edges with a trough-like depression extending between said supporting edges, and a recess in said trough to provide space for a plug in the bottom of an ingot mold.

4. The combination of a closed bottom ingot mold provided with supporting surfaces on the bottom thereof, and with an opening leading from the bottom of the matrix, a plug closing said opening and extending below the bottom of the mold, a trough-like supporting member comprising a trough-like structure provided with supporting rails adapted to cooperate with the surfaces at the bottom of the mold to support said mold vertically, said trough-like supporting member being provided with an opening into which said plug extends, and a depending portion on the bottom of said mold adapted to guide said mold into position between said supporting rails.

5. A supporting member for closed bottom ingot molds comprising a trough-like member with supporting rails on each side of the trough, and with a recess in the trough between said rails, said recess being adapted to accommodate a plug extending below the bottom of an ingot mold setting upon said support.

JOHN EDMUND PERRY.
